(73) Assignee: **Hon Hai Precision Ind. Co., Ltd.**,
Taipei Hsien (TW)

(57) **CLAIM**

(**) Term: **14 Years**

The ornamental design for a computer motherboard packaging box, as shown and described.

DESCRIPTION

(21) Appl. No.: **29/217,289**

(22) Filed: **Nov. 15, 2004**

(30) **Foreign Application Priority Data**

Jun. 28, 2004 (CN) 2004 3 0043834

(51) **LOC (8) Cl.** **09-01**

(52) **U.S. Cl.** **D9/652; D9/432**

(58) **Field of Classification Search** D9/600,
D9/651–653, 667, 669, 414, 430–433; 206/457,
206/459.1, 259.5, 822, 823, 799; 220/890

See application file for complete search history.
